CLAIM

The ornamental design for a refrigerator, as shown and described.

DESCRIPTION

1. Refrigerator

Reproduction 1.1 is a front perspective view of the refrigerator;

Reproduction 1.2 is a front view thereof;

Reproduction 1.3 is a back view thereof;

Reproduction 1.4 is a left view thereof;

Reproduction 1.5 is a right view thereof;

Reproduction 1.6 is a top view thereof;

Reproduction 1.7 is a bottom view thereof;

Reproduction 1.8 is a reference view showing the state in which the outer door has been opened and the mini-table has been unfolded; and

Reproduction 1.9 is a reference view showing the outer door and inner door have been opened.

(Continued)

The broken lines depict portions of the refrigerator that form no part of the claimed design; the fine lines on the drawings indicate the curved surface.
